ADJUSTABLE HITCH CLAMP

Filed Aug. 21, 1947

UNITED STATES PATENT OFFICE

2,474,078

ADJUSTABLE HITCH CLAMP

Earl Wilcox, Jr., Grand Junction, Colo.

Application August 21, 1947, Serial No. 769,948

2 Claims. (Cl. 280—33.44)

1

This invention relates to hitches or draft devices designed for attachment to an automobile bumper to facilitate towing and it is a primary object of the present invention to provide an adjustable clamp device for this purpose which will fit all types of automobile bumpers and may also be used as a clamp or gripping means upon other objects which are to be dragged, lifted or moved about.

A further and more specific object of the invention is to provide an adjustable tow clamp having a pair of jaw members connected by a chain whereby the jaw members may be readily coupled with opposite sides or edges of a body such, for example, as the top and bottom edges of a motor vehicle bumper, one of the jaws having an eye with which a tow cable may be readily connected.

Still another object of the invention is to provide an adjustable tow clamp of the character stated, wherein means is provided for tightening the chain between the jaws whereby to draw the jaws firmly into gripping engagement with a body placed between them.

The invention will be best understood from a consideration of the following detailed description taken in connection with the accompanying drawing forming a part of the specification, with the understanding, however, that the invention is not to be understood as limited to the exact details of construction shown and described since obvious modifications will occur to a person skilled in the art.

In the drawing:

Figure 1 is a view in side elevation of an adjustable tow clamp constructed in accordance with the present invention the same being shown applied to a vehicle bumper of arcuate form, which is in section.

Figure 2 is a view in front elevation of the same.

Figure 3 is a view in perspective of the lower jaw element.

Figure 4 is a view in top plan of the top jaw element.

Figure 5 is a sectional view taken longitudinally of the top jaw element and showing the clamp nut, the threaded bolt and a portion of the chain.

Figure 6 illustrates diagrammatically different forms of bumpers with which the tow clamp is adapted to be connected.

Referring now more particularly to the drawing the numeral 10 generally designates a motor vehicle bumper of transversely arcuate form upon

2

which is shown mounted the adjustable tow clamp of the present invention.

The present adjustable tow clamp comprises upper and lower jaw units 11 and 12, and a flexible intermediate or connecting unit 13, by means of which the upper and lower jaw units are adjustably coupled together to be drawn into gripping relation with the top and bottom edges of the vehicle bumper or other object to which the device is applied.

The upper jaw unit 11 comprises a plate body 14. This plate comprises the two obliquely angled portions *a* and *b*, the free end of the portion *b* being turned back upon itself to form the hook 15.

At the free end of the portion *a* of the plate is formed the eye 16 with which a tow cable or chain may be connected.

Extending longitudinally of the plate is a slot 17 and upon the top of the portion *a* there are formed at opposite sides of the slot 17 the transversely directed shoulders 18. The sides of these shoulders 18 adjacent to the portion *b* of the plate are inwardly curved or depressed as indicated at 18a whereby to form with the adjacent angle between the plate portions *a* and *b*, a rest or saddle 19 in which positions a shoulder block 20 which extends across the full width of the plate. This shoulder block has formed there-through a threaded passage 21 for the purpose hereinafter described and it is substantially semi-circular upon its underside as indicated at 22, to seat in the angle 19 and against the curved faces 18a of the shoulders 18.

The lower jaw unit 12 is also formed of a plate body of substantial length which is generally designated 23 and which is bent to provide the substantially parallel offset portions *c* and *d* which are connected by an obliquely angled intermediate portion *e*.

The free end of the portion *c* is turned back to form the hook 24 while the free end of the portion *d* is bent or curved slightly to form the backwardly turned lip 25.

In the angled portion *e* of the plate 23 is formed the circular aperture 26 into which opens the relatively narrow longitudinally extending slot 27 which is formed in the portion *d* and extends into the curved lip portion 25 all as illustrated in Figure 3.

The jaw units are connected together by the connecting unit 13 which comprises a link chain 28 which at one end carries the circular ring 28a while at the opposite end the chain is connected

with the eye 29 which forms an integral part of a threaded bolt 30.

The bolt 30 extends through the slot 17 of the upper unit and through the bore 21 of the shoulder block 20 and has threaded thereon the securing nut 31 which carries the lateral arms or wings 32.

As shown the lower end of the chain 28 is extended through the opening 26 and is then shifted outwardly so that one link of the chain lies in the narrow slot 27. The ring 28a forming the last link then is disposed cross-ways of the slot and there is thus formed the desired connection between the lower jaw and the chain.

By the provision of the rounded underside 22 for the shoulder block 20 it will be seen that the threaded bolt 30 can be readily disposed at any desired angle and thus the chain can be made to extend around and conform to the general contour of the bumper when the hooks 15 and 24 are engaged over the top and bottom edges of the bumper as shown. After the clamp has been placed in position in this manner rotation of the nut 31 will draw the chain tight so as to pull the jaws firmly into position. The tow cable or chain may then be attached to the eye 16 which extends forwardly from the upper unit.

Figure 6 illustrates in diagrammatic form the contours of different types of bumpers to which the clamp is adaptable. These bumpers which are designated 10' are of such form that only a tow clamp of the character herein disclosed could be applied thereto since the chain conforms generally to the contour of the bumper thereby making it possible to engage the upper and lower jaw members with the top and bottom edges of the bumper.

I claim:

1. An adjustable tow clamp comprising a pair of jaw members, each of said jaw members being

in the form of a relatively long plate having a portion of one end turned back to form a hook, one of the jaw members at its other end being formed to provide an eye for the attachment of a tow line thereto, the said one of the jaw members being bent transversely intermediate its ends to provide two obliquely angled portions, a slot formed in and extending longitudinally of the said one of the members, a chain connected at one end with the other one of the members, a relatively long threaded bolt connected to the other end of the chain and extending through said slot, a shoulder block disposed transversely of the said one of the members in the angle between the two portions, the shoulder block having an opening therethrough for the reception of said bolt, and a nut threaded upon the bolt and bearing against the shoulder block.

2. An adjustable tow clamp of the character stated in claim 1, wherein the said other one of the members has a circular opening therethrough at substantially the central part thereof and a slot leading from said opening toward the end of the member remote from the hook, the last mentioned slot being designed to have a link of the chain engaged therein whereby a terminal portion of the chain is disposed transversely of and against one face of the said other member.
